JOHN E. NORQUEST, OF RICHMOND, VIRGINIA, ASSIGNOR TO P. LORILLARD COMPANY, OF NEW YORK, N. Y., A CORPORATION OF NEW JERSEY.

PASTING MECHANISM FOR CIGAR AND CHEROOT MACHINES.

1,252,934.

Specification of Letters Patent.

Patented Jan. 8, 1918.

Application filed July 23, 1917. Serial No. 182,285.

To all whom it may concern:

Be it known that I, JOHN E. NORQUEST, a citizen of the United States, and residing at

5 Richmond, in the county of Henrico and State of Virginia, have invented new and useful Improvements in Pasting Mechanism for Cigar and Cheroor Machines, of which the following is a specification.

This invention relates to certain novel and 10 useful improvements in a pasting mechanism adapted particularly for applying paste to a leaf carried by the leaf carrier of cigar and cheroor making machines.

In the present instance, it is my purpose 15 to provide a pasting mechanism through the agency of which the paste may be uniformly and evenly applied to the leaf at certain predetermined times in the travel of the carrier.

20 In machines for making cigars and cheroors, a pasting mechanism is employed which is adapted to supply a dab of paste to a wrapper leaf on the leaf carrier.

The usual type of pasting mechanism is 25 of complicated structure, being composed of a relatively large number of parts and operated from a grooved cam wheel driven from the power mechanism of the machine. Furthermore, under varying conditions of 30 use, it is a difficult and tedious operation to adjust the various parts of the ordinary pasting mechanism in order to insure that the latter will properly supply the paste to the wrapper leaf at the proper moments 35 in the travel of the leaf carrier, and the result is that frequently, through mal-adjustment of the parts, there results not only an improper application of the paste, but also a wasting of the latter. Another disadvantage incident to the ordinary type of pasting

40 mechanism is that when, for any reason, one pasting mechanism must be discarded and another substituted, it is necessary to supply a new grooved cam wheel for the 45 train of operating mechanism, thereby involving considerable expense and delay, for the grooved track of such cam wheel must be cut with the greatest nicety to insure the proper operation at predetermined moments.

50 In the present instance, I have provided a pasting mechanism wherein the above mentioned disadvantages are obviated, for I dispense entirely with the grooved cam for operating the mechanism, and also so construct the other parts of the latter that the

paste will be uniformly and evenly distributed continuously and at the proper time.

Furthermore, it is my purpose to provide a pasting mechanism wherein the various 60 parts may be readily and instantly adjusted to accommodate such mechanism to varying conditions under which the machine is to be operated, thus insuring that such pasting mechanism will be brought into action at 65 precisely the proper moment to supply paste to the wrapper leaf on the leaf carrier.

It is also my purpose to provide a pasting mechanism which will embody the desired 70 features of simplicity, efficiency, and reliability; which will so operate as to accomplish a saving of paste while in operation; which may be adjusted to any selected position; and which will coöperate with other coacting parts of the machine in proper timed 75 relation.

With the above recited objects and others of a similar nature in view, my invention consists in the construction, combination, and arrangement of parts set forth in and 80 falling within the scope of the appended claims.

In the accompanying drawings:

Figure 1 is a view in side elevation of a 85 pasting mechanism embodying my invention, such view also illustrating the leaf carrier conventionally in dotted lines, and showing so much of the power mechanism as is necessary to understand the operation of my mechanism.

Fig. 2 is a top plan view of the mechanism shown in Fig. 1.

Fig. 3 is a perspective view of the paste-applying arm, and a portion of the operating devices thereof.

Fig. 4 is a detail sectional view of the connection between the crank arm and the link rod for actuating the pasting mechanism proper.

Referring to the accompanying drawings 100 in detail, the letter A indicates conventionally a portion of the side frame of the machine, while the well-known leaf carrier, which carries the wrapper leaf intended to receive the paste is conventionally shown in 105 dotted lines at B. The pasting mechanism is indicated as an entirety by the letter C, and is of course intended to supply paste to the tip end of a wrapper leaf on the leaf carrier B when the latter is positioned there- 110

over, as indicated in Figs. 1 and 2, this leaf carrier in the course of its operation swinging into position to deliver a wrapper leaf to the wrapping mechanism of the machine 5 as is well known in the art.

In the form of my invention shown herein, my pasting mechanism includes a bracket 1 fastened to the side frame of the machine and supporting the upwardly extending 10 slightly bowed standard 2, the latter being formed with a longitudinal web 3, the upper end of which is formed with a Y-shaped section 4, the arm 5 of which terminates in a bearing sleeve 6, while the other arm 7 15 terminates in the bearing sleeve 8. Mounted to turn within the sleeve 6 is a second sleeve 9 through which extends the rod 10, a set-screw 11 being employed to adjustably secure the rod 10 within the sleeve 9 and thus 20 permit said rod to be shifted longitudinally of the sleeve and then fastened in a selected position. Carried by this rod 10 is a block 11' bored as at 12 for the reception and passage of the paste-applying arm 13, a set-screw 14 being employed for adjusting the 25 arm 13 in the block 11' and thus lengthening or shortening the throw of the paste-applying arm. The block 11' is also intended to be adjusted lengthwise of its supporting rod 10 and may be either frictionally held on the latter or positively fastened as by the set-screw 15. The numeral 16 indicates a cam bar, one end of which terminates in a collar 17 adapted to fit over the outer 30 end of the rod 10 and to be fastened thereto in any suitable manner as by a pin or screw 18. This cam bar 16 is preferably formed of a piece of metal which is T-shaped in cross-section, as shown in Fig. 3, and adjacent the end 17 is formed with a V-shaped bend 19 constituting the operating or toe 35 section of the cam bar. The sleeve 8 of the standard has socketed therein a stop pin 20 which projects above this toe section of the cam bar and acts to limit the upward swinging movement of such cam bar as will be readily understood.

In order to rock the cam bar up and down, and thus elevate and depress the paste-applying arm 12, I employ a lever 21, the free 50 end of which is provided with a roller 22 adapted to ride against the under side of the cam bar, as shown in Fig. 1. This lever 21 is pivoted to rock upon the shaft 23 projecting from the standard 2 and the lower end of this lever is bent at an angle to the main portion thereof, as shown at 24. In order to rock the lever 21, I fasten a small crank arm 25 to the shaft 26 of the machine, which 55 may be the power shaft of the latter, or may be a separate shaft driven from the power shaft, and to the outer end of this crank arm 25 there is pivoted as at 26' a short swinging sleeve 27 in which is adjustably 60 threaded one end of the connecting rod 28,

the opposite end of this rod being threaded in the sleeve 29 pivoted at 30 to the lower end of the angular section 24 of the lever 21. The numeral 31 indicates a paste pot or receptacle of any suitable construction, and 70 which is fastened to the standard 2 so as to lie directly beneath the rocking paste arm 13, the free end of the latter being in the nature of a flattened coil 13' which is adapted to be dipped into the paste in the receptacle 31 75 on downward movement of the arm, and on the upward movement of the latter, is adapted to contact with the tip end of a wrapper leaf on the leaf carrier B, and to transfer paste to the leaf. The upper face of this 80 coil terminal 13' which contacts with the leaf is preferably flat, as indicated in Fig. 3, so as to uniformly and evenly apply the paste. By reference to Fig. 2, it will be seen that one side, or the outer side, of the paste pot 85 or receptacle is formed with a relatively flat or vertical wall, this being for the purpose of permitting the close mounting and adjustment of the operating mechanism for the paste-applying arm.

From the above description, taken in connection with the accompanying drawings, the construction and operation of my improved pasting mechanism will be readily apparent. In the rotation of the shaft 26, 95 when the machine is running, motion will be transmitted to the crank arm 25 and connecting rod 28 to the lever 21 to rock the latter on the shaft 23 and as the upper end of the lever is rocked back and forth, the 100 roller 22 will ride against the under face of the cam bar 16, and cause the elevation and permit the depression of the latter, consequently lifting the coiled end of the paste-applying arm 13 out of and dipping it into 105 the body of paste in the paste pot. In Fig. 1, it will be seen that the roller 22 is just about at the depression or toe of the cam bar and at this time, the latter is almost in its highest position of elevation, and consequently the paste-applying coil 13' at the 110 end of the arm 13 is in position to apply paste to a leaf carried by the leaf carrier B which latter has been brought to position directly over the paste arm by its actuating 115 mechanism.

As the roller 22 of the lever 21 leaves the toe end moving outwardly to the left, the cam bar 16, being unsupported by the roller, will drop down, thus gradually 120 lowering the paste arm into the receptacle 31, this taking place without splashing the paste or causing the formation of bubbles, as commonly occurs with the usual pasting mechanism employed in machines of this 125 class. On the return or forward stroke of the lever 21, the roller 22 will strike the toe of the cam bar 16 and lift the latter as shown in Fig. 1, thus causing the coiled end 13' of the paste-applying arm to be 130

brought into contact with and to apply a dab of paste to the tip end of the wrapper leaf carried by the carrier B. After passing the toe of the cam bar 16, the roller 22 will 5 move into contact with the straight section of the bar 16, first forward or toward the free end thereof and then backward or again toward the toe thereof, and this reciprocation of the roller 22 against the straight 10 section of this cam bar 16, due to the swinging movement of the lever 21, will cause the paste arm to drop away or be lowered relative to the leaf carrier, but will not permit it to enter the receptacle. This movement 15 of the paste carrying arm which might be termed a "dwell" will take place in order to allow the leaf carrier to move away from the paste applying mechanism before the lever 21 returns on its backward stroke and 20 contacts with the toe of the cam bar because the paste is only applied to the wrapper on the leaf carrier but once in each cycle of operation, or on the forward stroke of the lever 21, or its movement toward the right of 25 Fig. 1. At the time the roller 22 contacts with the toe of the cam bar 16 on the rearward movement of the lever 21, or its movement toward the left in Fig. 1, the leaf carrier is not in position directly over the 30 paste-applying arm, but has been moved away from the same and is in position at or adjacent to the wrapping mechanism of the machine. In other words, the lowering and dwelling movement imparted to the 35 paste applying arm 13, as above described, allows of the lapse of sufficient time for the leaf carrier to move away from the pasting mechanism before the paste applying arm of the latter can again be elevated.

40 By this cycle of operation, I insure that the arm will be brought in contact or will move in proper timed relation to apply the paste to the leaf carrier. It will further be seen that I practically attain a universal adjustment of the paste-applying arm by the 45 construction herewith shown, so that such arm may be shifted or adjusted to accommodate the particular machine on which it is to be used, or to compensate for such 50 variations as may be made in the adjustment of the machine or the leaf carrier. It will also be seen that should it be necessary to change the driving mechanism of my pasting mechanism, there will be no grooved 55 cam wheel to change or substitute on the shaft 26, as is commonly the case, as I have dispensed entirely with such grooved wheel and the cam roller commonly working therewith, employing in place thereof, the simple 60 arrangement of crank arm and connecting rod herein shown.

While I have shown and described one preferred embodiment of my invention, I wish it to be understood that I do not con-

fine myself to all the precise details of construction herein set forth by way of illustration, as modification and variation may be made without departing from the spirit of the invention or exceeding the scope of the appended claims. 65 70

I claim:

1. A paste-applying mechanism for cigar and cheroot machines comprising a paste-carrying element adapted to apply paste to a leaf on the leaf carrier of the machine, a paste receptacle located below the paste-applying element, and means for moving said element into and out of said receptacle and into and out of paste-applying position relative to the leaf carrier at predetermined times, said means including a rock shaft upon which the paste applying element is mounted, a cam bar also connected with the rock shaft and extending substantially in parallelism relative to the paste-applying element, a lever adapted to contact with the cam bar to move the latter up and down and to consequently actuate the rock shaft, and means for operating said lever. 75 80 85

2. A paste-applying mechanism for cigar and cheroot machines comprising a paste-carrying arm having a free end adapted to apply paste to a leaf on the leaf carrier of the machine, a paste-receptacle located below the paste-applying arm and means for moving the free end of said arm into and out of said receptacle and into and out of paste-applying position relative to the leaf carrier at predetermined times, said means including a rock shaft to which one end portion of the paste-applying arm is connected, a cam bar also connected at one end to said rock shaft and having a depending toe-portion, an oscillating lever pivotally mounted beneath the cam bar, and having its upper end portion adapted to be moved into contact with the cam bar to actuate the latter and consequently the rock shaft to elevate and lower the paste-applying arm, a power shaft, and a connection between the power shaft and the lower end of the lever for actuating said lever. 90 95 100 105 110

3. In a paste-applying mechanism for cigar and cheroot machines, a paste-receptacle, a rock shaft extending thereabove, a paste-applying arm mounted on the rock shaft and extending laterally therefrom and adapted to be moved into and out of the receptacle and into and out of paste-applying position relative to the leaf carrier of the machine, a laterally extending cam bar also extending from the rock shaft, a pivoted lever mounted below the cam bar and adapted to oscillate in contact with such cam bar to operate the rock shaft and consequently the paste-applying arm, and means for oscillating said lever. 115 120 125

4. In a paste-applying mechanism for ci-

gar and cheroot machines, a paste receptacle, a rocking member positioned above the receptacle, a paste-applying arm connected with and extending laterally from the rocking member, means for adjusting said paste-applying arm longitudinally of the rocking member, means for adjusting said arm transversely of said rocking member, and means for imparting a rocking movement to the 10 rocking member to elevate and depress the paste-applying arm relative to the receptacle, said last mentioned means including a cam bar connected with the rocking member and extending substantially in parallelism with the paste-applying arm, a pivoted cam lever mounted beneath and adapted to oscillate in contact with the cam bar, and

devices for oscillating said pivoted cam lever.

5. In a paste-applying mechanism, the 20 combination with a paste-holding receptacle, of a rocking support located adjacent thereto, a paste-applying element adjustably attached to the rocking support, said element including an arm having one end terminating in a coil, and means for moving the coil terminal of the element into and out of the receptacle, said means including a lever for actuating the rocking support, and a crank and connecting rod for operating the lever. 25 30

In testimony whereof I have hereunto set my hand.

JOHN E. NORQUEST.
